US0D1031436S

(12) **United States Design Patent** (10) Patent No.: **US D1,031,436 S**
Fore et al. (45) Date of Patent: ** Jun. 18, 2024

(54) **ACTUATOR**

- (71) Applicant: **PRECISION VALVE CORPORATION**, Greenville, SC (US)
- (72) Inventors: **John B. Fore**, Travelers Rest, SC (US); **Michael P. Downey**, Greer, SC (US); **Matthew L. Brett**, Toronto (CA)
- (73) Assignee: **Precision Valve Corporation**, Greenville, SC (US)

(**) Term: **15 Years**(21) Appl. No.: **29/811,683**(22) Filed: **Oct. 15, 2021**(51) LOC (14) Cl. **09-07**

(52) U.S. Cl.

USPC **D9/448**; D9/453

Primary Examiner — Darcey E Gottschalk*(74) Attorney, Agent, or Firm* — Ruggiero McAllister & McMahon LLC(57) **CLAIM**

The ornamental design for an actuator, as shown and described.

DESCRIPTION

FIG. 1 is a perspective view of an actuator showing our design;

FIG. 2 is a rear view thereof;

FIG. 3 is a left view thereof;

FIG. 4 is a right view of thereof;

FIG. 5 is a front view thereof;

FIG. 6 is a top view thereof; and,

FIG. 7 is a bottom view thereof.

In the drawings, the broken lines show portions of an actuator that form no part of the claim.
